UNITED STATES PATENT OFFICE.

PHILIP H. WEBER, OF HOOPESTON, ILLINOIS.

SHOCK-ABSORBER.

1,263,494.

Specification of Letters Patent. Patented Apr. 23, 1918.

Application filed June 9, 1915. Serial No. 33,105.

To all whom it may concern:

Be it known that I, PHILIP H. WEBER, a citizen of the United States, residing at Hoopeston, in the county of Vermilion and State of Illinois, have invented certain new and useful Improvements in Shock-Absorbers, of which the following is a specification, reference being had to the accompanying drawings.

10 This invention comprehends certain new and useful improvements in shock absorbers of the type that act in the nature of auxiliary springs, and the present invention is designed particularly for use in connection with Ford motor cars, although it is not necessarily limited thereto.

The invention has for one of its principal objects a durable and efficient construction of device of this character, the parts of which may be very easily made and readily assembled and not liable to get out of order and which will effectively serve to reinforce and protect the action of the main springs of the vehicle so as to make same ride more comfortably and at the same time protect the springs from injury, particularly in connection with the rebound.

A further object of the invention is a device of this kind which may be very easily applied to the vehicle, capable of being manufactured at a reasonable cost, and which will have balanced bearing and evenly distribute the wearing surfaces, thereby lengthening the life of the device and adding materially to the flexibility of the springs, as well as increasing the strength thereof.

And the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawings, in which,

Figure 1 is an elevation of a rear axle with my device applied thereto.

Fig. 2 is a similar view of a front axle.

Fig. 3 is a detail view of one of the main portions of the device.

Fig. 4 is a detail view of one of the saddles or clevises employed.

Corresponding and like parts are referred to in the following description and designated in all of the views of the accompanying drawing by like reference characters.

Referring to the drawing and now particularly to Fig. 1, the numeral 1 designates a rocker which may be formed as a forging or casting and which is preferably arched or bowed from end to end so as to give maximum strength with minimum weight. The rocker 1 is formed at one end with two laterally spaced arms 2, designed to straddle or embrace the main spring 3 at the rear of the vehicle, and at its other end the rocker is forked, as indicated at 4, the forked extensions being formed at their extremities with apertured ears 5 designed to be pivotally connected by a bolt 6 or the like, to the clip 7 which is otherwise connected by links 8 to the spring 3. In the present embodiment of the invention and arrangements of the parts these links 8 pivotally connect the end of the spring 3 to the rocker 1 intermediate of the ends of the latter, and near the forked end 4, as clearly illustrated in the drawing. The arms 2 of the rocker 1 are formed at their extremities with apertured ears 9 designed for engagement with hooks that are formed on one end of contractile springs 10, and the hooks at the other ends of the springs 10 are designed for engagement in the coiled extremities of an arched saddle or clevis 11 that is adapted to extend over and rest upon a casing or bracket 12 secured in any desired way upon the transverse spring attaching bar 13.

From as much of the description as has preceded in connection with the correlated views of the accompanying drawing, it will be clearly understood that the action of the main spring 3 will be effectively reinforced and protected by means of the rocker arms 1 that are, of course, arranged in pairs, as shown, and that are pivotally connected intermediate of their ends to the ends of the spring 3, and that are further connected at one end to the clip 7 and at their other ends to the spring attaching bar 13 of the vehicle body by means of the contractile springs 10 and brackets 12 and that therefore the ve-

hicle will ride more easily while at the same time the flexibility of the spring is augmented without detracting at all from the strength thereof, but in reality adding materially to the main spring 3.

Referring now to Fig. 2, where the invention is shown as associated with the front axle F instead of the rear axle R, it will be seen that the parts are substantially the same and that the only difference is in the manner of application. For example, when the devices are connected to the front axle F and the front body main spring 3', the forked ends of the rockers 1 are pivotally connected to the axle by means of links 14, and that the upwardly converging springs 10 are connected at their upper ends by a clevis 15 to the front spring attaching bar 16. But the construction of the parts is the same as well as the operation thereof.

While the accompanying drawing illustrates what I believe to be the preferred embodiment of my invention, it is to be understood that the invention is not limited thereto, but that various changes may be made in the construction, arrangement and proportions of the parts without departing from the scope of the invention as defined in the appended claims.

What is claimed is:—

1. A shock absorber for vehicles, comprising a rocker attached at one end to the vehicle axle and intermediate its ends to the spring of the vehicle, and formed at its other end with laterally spaced arms projecting below the plane of said vehicle spring, and a contractile spring connected to each of said arms and attached to a portion of the vehicle body.
2. A shock absorber for vehicles, comprising a rocker attached at one end to the vehicle axle and intermediate its ends to the spring of the vehicle, and formed at its other end with laterally spaced arms straddling said vehicle spring, and a contractile

spring connected to each of said arms and attached to a portion of the vehicle body.

3. A shock absorber for vehicles, comprising an arched rocker attached at one end to a vehicle axle and intermediate its ends to the end of the spring of the vehicle, said rocker being formed at its other end with laterally spaced arms straddling said vehicle spring, contractile springs each connected at one end to each of said arms, and a saddle connected to the other ends of said springs and resting on a portion of the vehicle body.

4. The combination with the axle of a vehicle, the main spring thereof, and the spring attaching bar thereof, of a rocker pivotally connected intermediate its ends to said spring and pivotally connected at one end to the axle, said rocker being formed at its other end with laterally spaced arms having apertured extremities and straddling said main spring, contractile springs having hooks at one end engaged in the apertured extremities of the rocker and provided with hooks at their other ends, a bracket secured to the spring attaching bar, and a saddle having curled ends engaging the last-named hooks and resting upon the bracket.

5. In combination, spaced apart brackets, members pivotally connected to the brackets extending toward each other, shackles pivotally secured to and depending from the members, a leaf spring carried by and between the shackles, a forked extension to each member having arms extended downwardly and inwardly in front and back of the leaf spring, and a coiled spring under tension secured to the end of each arm.

In testimony whereof I hereunto affix my signature in the presence of two witnesses.

PHILIP H. WEBBER.

Witnesses.
